UNITED STATES PATENT OFFICE.

ERNST PHILIPP HINKEL, OF OFFENBACH-ON-THE-MAIN, GERMANY.

ALBUM-CLASP.

SPECIFICATION forming part of Letters Patent No. 405,473, dated June 18, 1889.

Application filed February 12, 1889. Serial No. 299,616. (No model.) Patent in Germany October 11, 1888, No. 45,772.

To all whom it may concern:

Be it known that I, ERNST PHILIPP HINKEL, a subject of the Emperor of Germany, residing at Offenbach-on-the-Main, Germany, have 5 invented new and useful Improvements in Album-Clasps, (for which I have received Letters Patent in Germany dated October 11, 1888, No. 45,772,) of which the following is a specification.

10 My invention relates to an improvement in album-clasps, and has for its object to provide a clasp of simple, durable, and economical construction, which may be adjusted to an increased thickness of the album in a convenient and expeditious manner.

15 The invention consists in the novel construction and combination of the several parts, as will be hereinafter more fully set forth, and pointed out in the claims.

20 Reference is to be had to the accompanying drawings, forming a part of this specification, in which similar figures of reference indicate corresponding parts in all the views.

Figure 1 is a front elevation of an album 25 having my improved clasp applied thereto, said clasp being illustrated as in a locked position. Fig. 2 is an end view of the album, illustrating the clasp in a side elevation and in a locked position. Fig. 3 is an end view 30 of the album, illustrating the clasp attached thereto as unlocked. Fig. 4 is a central vertical section through the body of the clasp. Fig. 5 is a transverse section on line $x-x$ of Fig. 4. Figs. 6 and 7 are partial vertical sections of the several parts of the body of the clasp detached; and Fig. 8 is a partial side elevation of an album, illustrating the attachment thereto of a keeper-plate.

35 It is well known that albums increase in thickness as the number of photographs introduced therein increases, and that when an ordinary or unyielding clasp is attached to an album the said clasp produces a deformation of the cover when the book is closed. I am 40 aware, however, that clasps have heretofore been made which adjust themselves automatically to the book, and my invention is a clasp of the above-named type.

To the opposite sides of the album 45 plates 11 and 12 are secured in any approved man-

ner, which plates are preferably attached near the front edge of the cover and extend over the edge of the same, as illustrated in Fig. 1. The plate 11 is adapted to act in the capacity of a hinge-plate, and the plate 12 as a keeper 55 or clasp-plate. To that end the plate 12 is provided upon the upper edge, preferably at the center, with two spaced buttons 13, capable of receiving one extremity of the clasp, as will be hereinafter described. The hinge- 60 plate 11 is provided upon the outer or edge surface near each end with a lug or head 14, in which the pintles 15 of a preferably cylindrical bar 16 are journaled, the said bar 16 constituting a portion of the clasp. The body 65 of the clasp is constructed in two parts 17 and 18, and both sections 17 and 18 are tubular. The section 17, however, is of greater diameter than the section 18, and is secured at one end in any approved manner to the hinged bar 16, 70 as best illustrated in Fig. 7. In the tubular section 17 a coil or spiral spring 19 is longitudinally held, the outer end of which spring is free, and the inner end rigidly fastened to the back of the said section 17, as 75 best illustrated in Fig. 4. The smaller tubular section 18 is adapted to telescope within the section 17, and from the inner surface of the said smaller section 18, at the inner end, a lug or nose 20 is inwardly projected, adapted to 80 engage with the spring between the coils or spirals when the two sections of the body are united, as shown in Fig. 4. The outer end of the smaller or inner section 18 is closed, and from the said closed end a neck 21 is projected, terminating in a ball 22 or equivalent ornament.

In locking the clasp the neck 21 is made to pass between the two buttons 13 of the clasp-plate, and is prevented from falling out of 90 contact with the said buttons by reason of the contact of the ball 22 with the neck of the said buttons below the head, as illustrated in Fig. 1.

It will be readily observed that by turning 95 the outer end of the inner section 18 of the body of the clasp either to the right hand or to the left the reach of the clasp can be either lengthened or shortened at will, and in this manner the clasp can be easily adapted to a 100

book, whether it be thick or thin. It will be further observed that by reason of the attachment of the two sections in the manner above described the clasp will at all times 5 have a certain amount of elasticity.

Having thus described my invention, I claim as new and desire to secure by Letters Patent—

1. In an album-clasp, the combination of two telescopic sections and a spring secured 10 in one section and adjustably connected to the other section, substantially as described.

2. In an album-clasp, the combination of two telescopic sections, one of the sections being provided with a nose or lug, and a spiral 15 spring secured in one section and receiving the nose or lug of the other section between its spirals, substantially as herein shown and described.

3. In an album-clasp, the combination, with 20 a hinge and keeper plate, of a hinged cylindrical section, a smaller cylindrical section fitting in the hinged section and provided with a nose or lug and adapted to engage the keeper-plate, and a spring secured in the

hinged section and having its spirals engaged 25 by the nose of the smaller section, substantially as specified.

4. The combination, with a hinge-plate and a hinge-bar journaled thereon, of a clasp consisting of two tubular telescopic sections, the 30 outer section provided with a longitudinally-disposed spiral or coil spring rigidly secured at one end, and an inner section having a lug or nose projected downward from the inner end, capable of contact with the said spring 35 between the said coils; a locking device integral with the outer end, and a clasp-plate provided with spaced buttons adapted to receive the locking device, all combined for operation substantially as shown and described. 40

In testimony whereof I have signed my name to this specification in the presence of two subscribing witnesses.

ERNST PHILIPP HINKEL.
